TUBE END FORMING HAND TOOL

George E. Kjellberg, Lake Worth, Fla.

Application December 12, 1952, Serial No. 325,647

2-Claims. (Cl. 81—15)

This invention relates to hand forming-tools, and more particularly is directed to tools for shaping and forming lead pipe sections.

Lead pipe sections are employed by the plumbing trade to connect fixtures, such as commodes, bath tubs, wash basins, and the like, with the soil pipe system. It is necessary to slightly restrict the end of the pipe to make these connections. Prior practices are to form this restriction by using a hand tool with which the end section of the pipe is pounded in successive sections, sometimes while turning the pipe. This is a time consuming, laborious task, which is further limited in that the deformed or restricted end section is not true in circular cross-section.

Accordingly, an object of this invention is to provide a hand tool which will form and restrict an end section of lead pipe with one impact blow.

Another object of this invention is to provide a hand tool of the class described that will form a lead pipe section and restrict the end section thereof in true circular cross-section.

Another object of this invention is to provide a hand tool of the class described that will be economical and simple in construction, and efficient, durable and accurate in use.

The foregoing and other objects and advantages will be more apparent from reading the following specification in conjunction with the drawings, forming a part thereof, wherein:

Fig. 1 is a perspective view of the end section of a length of lead pipe;

Fig. 2 is a vertical cross-sectional view of the tool of this invention, with a pipe section partially shown in elevation;

Fig. 3 is an end view of the tool of this invention;

Fig. 4 is a cross-sectional view of a modification of the tool of this invention, parts shown in elevation; and,

Fig. 5 is a side elevation of the invention with handle embodiment added.

Referring to the drawings wherein like members are given the same reference numeral, a section of lead pipe 1 is generally represented having deformations 2 in the periphery thereof. The hand tool of this invention, which corrects the deformations and restricts the end to meet specification requirements for fittings is formed of any suitable rigid material, such as wood, aluminum, brass and the like, in any suitable manner, such as turning, spinning, casting and the like, depending on material employed. The preferred material and method is centrifugal cast aluminum. When a wooden tool is turned, it is desirable, if not essential, to turn the tool from a laminated block, in a conventional manner, to prevent splitting.

The tool has a hollow, open-end, cup-shaped body 3, preferably circular for economy of material consideration, having a vertically extending projection or boss 4, which is preferably cylindrical for economy of material and simplicity of construction. The hollow, open-end

2

body 3 has a cavity forming an inner circular wall 6, tapering upwardly and inwardly from the open end thereof; and the cavity inner wall 6 terminates in a channel defined by the wall 6, a horizontal annular flat section or shoulder 7 and an inwardly and downwardly sloping or tapered wall 8 of a downward projection 9, extending into the cavity and concentric therewith.

A vertical concentric cylindrical recess 11 is provided through the cylindrical projection 9 into the boss 4 as a further economy in material.

The cylindrical boss 4 may be provided with an annular projection 12 at the top end thereof, as illustrated in Fig. 4, as a hand protector. The boss 4 may also be provided with a handle, having a yoke 14 with apertures 15 therein to receive a pivot pin 17 extending through the boss 4.

The hollow body 3 may be modified to provide a bell-shaped interior wall 16, as illustrated in Fig. 4, to accommodate extremely deformed pipe sections to be formed and restricted.

The preferred form of the invention is best illustrated in Fig. 3 in which all elements are concentric in plan view, top or bottom.

Certain details of construction become important in production, and others are more important in use. When the device is to be cast from metal, such as aluminum, it is desirable to have the vertical exterior and interior surfaces of the body 3 and projection boss 4 sloping outwardly and downwardly to facilitate removal from the mold. It is also desirable to have the top surface of the boss 4 substantially flat to receive direct impact blows of a mallet. This boss 4 should also be of sufficient length to be firmly gripped by the hand or thumb and two fingers of the operator below the top of the boss to prevent possibility of smashed fingers.

When used with extremely deformed pipes the open end should be flared to bell-shape as illustrated at 16 in Fig. 4.

The circular interior wall 6 or 16 is preferably arcuately tapered upwardly, but straight line taper is satisfactory. The annular horizontal flat section 7 should be at least the width of the pipe wall, and preferably slightly wider to permit slight tolerance and clearance.

When substantially true circular lead pipe is to be restricted the internal projection 9 could be eliminated as it functions principally as inside pipe former, but it is desirable. With deformed pipe sections, it is essential.

The open end of the body 3 of the tool should measure at least $\frac{1}{4}$ inch and preferably $\frac{1}{2}$ inch greater inside diameter than outside diameter of pipe section to be restricted. The side wall 6 should terminate at the flat horizontal section 7 in a reduced diameter desired. The sloping interior side wall 6 should have a length approximately equivalent to the radius of the horizontal circular cross-section thereof. As example, to form a 4 inch pipe for connection to a toilet, the tool should be at least $4\frac{1}{8}$ inches in interior diameter at the open end, $3\frac{1}{8}$ inches in interior diameter at the junction of the side wall 6 and horizontal section 7, and have a 2 inch interior depth or length of the side wall.

When the tool is formed of aluminum it is desirable to apply wax to the end of the pipe section before restricting. Since wax is used on the restricted end when capping, this procedure merely adds the wax earlier than normally done, and it facilitates removal of the restricted pipe section. When wooden tools are used, the wax need not be added to the pipe until ready for capping.

In use the device is quite simple and can be used by unskilled labor. The tool is placed over the section of pipe, and the top of the boss 4 struck once with a mallet, thus driving the tool down on the pipe until the end of the pipe abuts the horizontal flat section 7. The wall 6 or 16

shapes and restricts the pipe in true circular cross-section. The internal projection 9 helps form badly deformed pipe sections.

This invention has been described in detail, but it is clearly understood that the invention is not so limited. Changes can be made therein without departing from the spirit and scope of the invention, as defined in the appended claims.

Having thus described the invention, what is claimed is:

1. A hand forming-tool comprising a body, an open-end cavity in said body, said cavity having a circular cross-section of diminishing diameter from said open end to the closed end thereof, a tapered concentric projection extending into said cavity, said projection being of lesser depth than the circular wall of the cavity and said projection defining an annular channel with the wall of said cavity and a horizontal annular flat section joining the wall of the cavity to the base of the projection.

10
15

2. A hand forming-tool comprising a vertically disposed body, an open-end cavity in said body, said cavity having a horizontal circular cross-section of upwardly diminishing diameter, and a vertically extending tapered cylindrical projection on said body concentric with said cavity and of lesser extent than the circular wall of the cavity.
